United States Patent Office

Des. 210,405
Patented Mar. 5, 1968

210,405

LOCKET

David Weissmann, Palos Verdes Estates, Calif., assignor
to Mattel, Inc., a corporation of California

Filed Mar. 1, 1967, Ser. No. 6,021

Term of patent 14 years

(Cl. D45—15)

FIGURE 1 is a front elevational view of a locket showing my new design;

FIGURE 2 is a side elevational view thereof, the side opposite being identical;

FIGURE 3 is a top plan view thereof;

FIGURE 4 is a rear elevational view thereof;

FIGURE 5 is a cross-sectional view taken along line 5-5 of FIGURE 4; and

FIGURE 6 is a bottom plan view of FIGURE 4.

I claim:

The ornamental design for a locket, as shown and described.
